US0D1032653S

(12) **United States Design Patent** (10) **Patent No.:** **US D1,032,653 S**
(45) **Date of Patent:** **** Jun. 25, 2024**

(54) **DISPLAY SCREEN OR PORTION THEREOF
WITH GRAPHICAL USER INTERFACE**

(71) Applicant: **Apple Inc.**, Cupertino, CA (US)

(72) Inventors: **Pablo F. Caro**, San Francisco, CA (US); **Dmitri Cavander**, San Francisco, CA (US); **Matthew Wagner Crowley**, Sunnyvale, CA (US); **Charmian Naguit**, San Francisco, CA (US)

(73) Assignee: **Apple Inc.**, Cupertino, CA (US)

(**) Term: **15 Years**

(21) Appl. No.: **29/856,790**

(22) Filed: **Oct. 17, 2022**

Related U.S. Application Data

(63) Continuation of application No. 29/834,462, filed on Apr. 12, 2022, now Pat. No. Des. 967,171, which is (Continued)

(51) **LOC (14) Cl.** **14-04**

(52) **U.S. Cl.**

USPC **D14/486**

(57) **CLAIM**

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a display screen or portion thereof with graphical user interface showing the claimed design; and,

FIG. 2 is another embodiment thereof.

The broken lines in the figures show a display screen or portion thereof, and form no part of the claimed design.

**1 Claim, 2 Drawing Sheets
(1 of 2 Drawing Sheet(s) Filed in Color)**

Related U.S. Application Data

a continuation of application No. 29/738,841, filed on Jun. 19, 2020, now Pat. No. Des. 951,287.
